UNITED STATES PATENT OFFICE.

ADOLF EGGLI, OF COLOGNE, GERMANY, ASSIGNOR TO E. W. SCHLAPPITZI, OF MINNEAPOLIS, MINNESOTA.

SPRING STRUCTURE FOR SEAT CUSHIONS.

Application filed December 26, 1924. Serial No. 758,270.

This invention relates to spring structures for seat cushions and relates particularly to cushion structures employing leaf springs.

The invention consists in the structural features and arrangement of parts hereinafter fully described.

In the drawings:—

Figure 1 is a plan view of the improved spring structure;

10 Figure 2 is a side view of the same;

Figure 3 is an end view;

Figure 4 is an enlarged view of a clip connecting two transverse tie members;

15 Figure 5 is a detail section on line 5—5 of Figure 4.

In these views the reference character A designates a bottom border frame comprised by an endless rod or hoop bent to form approximately a rectangle with rounded corners. Said frame has its central portion reinforced by a pair of braces A', preferably angle bars, connecting the front and rear members of the frame, and a pair of bars A² parallel to said front and rear members and riveted or otherwise rigidly secured to the braces A' form a further reinforcement. Preferably the rear bar A² extends substantially the full length of the spring structure and is secured by clips A³ to the ends of the 20 border frame A. The end portions of the bottom frame are respectively reinforced by braces A⁴ parallel to the braces A' and extending from the rear bar A² to the front member of the bottom frame, being secured to the latter by clips A⁵. The braces A⁴ are connected also to the ends of the frame A by short links A⁶. The top frame comprises simply a 25 border member B formed preferably of a resilient metal rod similar to that used in the bottom frame and corresponding in contour to the latter. The member B, however, preferably employs no rear connecting portion between its ends, this being best seen in Figure 1. For resiliently mounting the top frame upon the lower one there is employed a plurality of leaf springs C, each of an approximate semi-circular shape, said springs being arranged, preferably in opposed pairs, riveted or otherwise secured to the bars A² of the bottom frame, the ends of the opposed

springs being convergent. The upper ends of each pair of opposed springs are connected by a pair of tie members D formed of spring metal, the same being preferably riveted to the springs C. Said tie members are extended forwardly beyond their points of connection with the front row of springs C, as indicated at D', said portions D' being terminally secured by clips D² to the front portion of the top frame B. Thus the extensions of said tie members constitute a primary means for supporting the top frame upon the springs. A secondary means for that purpose is formed by a pair of links E which extend from the end ties D to the end portions of the top frame.

The end pairs of leaf springs C are opposed in a more closely adjacent relation than the intervening springs owing to the reduction of space resulting from the rounded corners of the frames A and B. F is a reinforcing strap formed of spring metal and connecting the tie members D substantially along the longitudinal center line of the top frame. Said strap, as shown, is riveted at F' to one tie member of each pair and is connected to the other tie member by a sheet metal clip F² providing for a slight sliding movement between said strap and the ties. Each of the leaf springs C is provided with a reinforcement which takes effect under predetermined conditions of severe stress. Thus an arcuate leaf spring G is interiorly secured to each spring at substantially a mid height, preferably by a rivet G'. The curvature of the reinforcing springs G is of lesser radius than that of the main springs so that the latter come into reinforcing engagement with the former only under conditions of considerable distortion, as shown in Figure 5.

Considering the structure now more fully with respect to the functions of its various parts it will be readily understood that the top border frame B coacts with the tie members D to support the top upholstery (not shown) of a cushion. Under load the tie members D and likewise the longitudinal reinforcing strap F will yield downwardly, stressing the leaf springs C. If the weight resting upon the structure is unusually severe the

main springs C will engage the auxiliary springs G and be reinforced thereby. The clip connections D² between the tie members D and the top frame B are free to turn upon 5 said frame when the tie members are depressed under load.

The resilient nature of the rod B forming the top frame permits the end portions thereof to function as springs tending to maintain 10 the longitudinal strap member F normally taut and in the plane of said frame. When the structure is under stress, however, all or any portion of said strap member may be 15 downwardly deflected, this being permitted by a yielding of the ends of the top frame toward each other. When the structure is relieved of load the end portions of the top spring will return to their maximum spaced 20 relation, straightening said strap.

25 The sliding connections between the strap F and the tie members D secured where the links E are employed to establish such connections, permit such limited relative transverse movement of said strap and ties as may be required by conditions of stress.

It is to be observed that both the top and bottom frames have a greater extent from front to back and also from end to end than the springs C so that the fabric covering 30 which is to be mounted upon the described structure will be engaged solely with said top and bottom frame and not subjected to wear and deterioration by contact with the springs.

What I claim as my invention is:—

35 1. A top frame for a spring cushion structure comprising a rod extending along the front and ends of said structure having all portions spaced from the lower frame of said structure, said frame being open at its rear, 40 the rear extremities of the ends of said frame being curved toward each other.

45 2. A spring structure for cushion seats comprising top and bottom frames, the former having resilient end portions integral with the front portion, springs intermediate said frames, and a connection between said end portions normally maintained thereby substantially in the plane of the top frame and adapted for deflection under load through 50 stressing of said end portions toward each other.

55 3. A spring structure for cushion seats comprising top and bottom frames, the former having resilient end portions integral with the front portion, springs intermediate said frames arranged in parallel rows, tie members connecting the upper ends of the springs of said rows, and a connection between said resilient end portions transversely 60 engaging said tie members, said connection being adapted for deflection under load through stressing of said end portions toward each other.

4. A spring structure for seat cushions

comprising top and bottom frames, the former having resilient end portions integral with the front portion, leaf springs arranged in opposed pairs and mounting the top frame on the bottom frame, a series of substantially parallel tie members connecting said leaf 65 springs at the top of the structure, and a tie member transversely engaging the first mentioned ties and connected to the ends of said top frame, said ends yielding inwardly under stress to permit downward deflection of 70 said tie member connecting the same.

5. A spring structure for cushion seats comprising a bottom frame, and a top frame formed by a rod comprising front and end portions only, said end portions being 80 resilient and free at their rear extremities, springs mounting said top frame on the bottom frame and a tie connection between the end portions of the top frame adapted for downward deflection under stress through 85 springing of said portions toward each other and normally held substantially in the plane of the top frame by said portions.

6. A spring structure for seat cushions comprising top and bottom frames, one of 90 which has resilient end portions integral with the front portion thereof, springs intermediate said frames, and a connection between said end portions normally maintained thereby substantially in the plane thereof.

95 7. A spring structure for cushion seats comprising a bottom frame having a continuous rod as its peripheral portion, and a top frame formed by a rod comprising front and end portions only, said end portions being 100 resilient and free at their rear extremities, springs mounting said top frame on the bottom frame, and a tie connection between the end portions of the top frame adapted for a downward deflection under stress through 105 springing of said portions toward each other and normally held substantially in the plane of the top frame by said portions.

110 8. A spring structure for cushion seats comprising a pair of spaced frames, each of 110 said frames having an integral rod as its peripheral member, the peripheral member of the lower frame providing a complete enclosure, the peripheral member of the upper frame conforming substantially to the contour of the lower frame, but having no rear portion, the end portions of said upper peripheral member being resilient, springs mounting said top frame on the bottom frame, and a tie connection between the end 115 portions of the top frame adapted for downward deflection under stress through springing of said portions toward each other and normally held substantially in the plane of the top frame by said portions.

120 125 9. A spring structure for cushion seats comprising top and bottom frames, the former having resilient end portions integral

with the front sections, leaf springs arranged in opposed pairs and mounting the top frame on the bottom frame, tie members connecting the paired leaf spring at the top thereof and 5 extended to engage and support the top frame, a transversely extending member connected at its ends to the outer tie members, and transverse members extended between and connected at their opposite ends to said outer tie members and said resilient end members. 10

In testimony whereof I affix my signature.

ADOLF EGGLI.
